CLAIM

The ornamental design for a tracheostomy tube, as shown and described.

DESCRIPTION

FIG. 1 is a top, front and left side perspective view of a tracheostomy tube in a first position;

FIG. 2 is bottom, front and right side perspective view of the tracheostomy tube shown in FIG. 1;

FIG. 3 is a front plan view of the tracheostomy tube shown in FIG. 1;

FIG. 4 is a bottom, rear and left side perspective view of the tracheostomy tube shown in FIG. 1;

FIG. 5 is a rear plan view of the tracheostomy tube shown in FIG. 1;

FIG. 6 is a top, front and left side perspective view of the tracheostomy tube shown in FIG. 1 in a second position;

FIG. 7 is a front plan view of the tracheostomy tube shown in FIG. 6; and,

FIG. 8 is a rear plan view of the tracheostomy tube shown in FIG. 6.
